CLAIM

The ornamental design for a computer peripheral, as
shown and described.

DESCRIPTION

FIG. 1 is a perspective view of a computer peripheral
showing our new design;

FIG. 2 is a front elevational view thereof on an enlarged
scale;

FIG. 3 is a rear elevational view thereof on an enlarged
scale;

FIG. 4 is a right side elevational view thereof on an
enlarged scale;

FIG. 5 is a left side elevational view thereof on an enlarged
scale;

FIG. 6 is a top plan view thereof on an enlarged scale;
and

FIG. 7 is a bottom plan view thereof on an enlarged
scale.
